UNITED STATES PATENT OFFICE.

MARY C. PAYNE, OF SOUTH HAVEN, MICHIGAN.

DESIGN FOR A DUST-PAN.

SPECIFICATION forming part of Design No. 23,676, dated October 2, 1894.

Application filed August 22, 1894. Serial No. 521,037. Term of patent 14 years.

To all whom it may concern:

Be it known that I, MARY C. PAYNE, a citizen of the United States, residing at South Haven, in the county of Van Buren and State of Michigan, have invented a new and original Design for Dust-Pans, of which the following is a specification.

The invention relates to a new and original design for dust pans.

- o The object of the present invention is to provide an attractive dust-pan possessing an ornamental and useful form, and the essential feature resides in an inclined dust-pan provided with a curved truncated elliptical handle extending downward and rearward from the back of the pan, and upward and forward, and terminating in a Y-shaped extension, having diverging arms arranged beneath the pan.
- o In the drawings—Figure 1 is a perspective view of a dust-pan showing my new and original design. Fig. 2 is a vertical sectional view, the handle being shown in elevation.

Referring to the drawings, 1 designates an inclined dust-pan provided at its back with 25 a handle 2, having a truncated elliptical shape. The upper portion of the handle curves rearward and downward from the back of the dust-pan, and then upward and forward, and the lower portion of the handle, 30 terminates in a Y-shaped extension 3. The Y-shaped extension is arranged beneath the pan, and the arms 4 and 5 extend upward to the lower face of the pan. At the back of the handle is a ring 6. 35

What I claim is—

The design for a dust-pan herein shown and described.

In testimony that I claim the foregoing as my own I have hereto affixed my signature in 40 the presence of two witnesses.

MARY C. PAYNE.
